UNITED STATES PATENT OFFICE.

JOHN E. HOWELL, OF SACRAMENTO, CALIFORNIA.

LAWN-HOSE HOLDER.

1,192,313.

Specification of Letters Patent. Patented July 25, 1916.

Application filed September 7, 1915. Serial No. 49,175.

To all whom it may concern:

Be it known that I, JOHN E. HOWELL, a citizen of the United States, residing at Sacramento, in the county of Sacramento, State of California, have invented certain new and useful Improvements in Lawn-Hose Holders; and I do declare the following to be a clear, full, and exact description of the same, reference being had to the accompanying drawings, and to the characters of reference marked thereon, which form a part of this application.

This invention relates to improvements in standards or supports for holding lawn hose during the sprinkling operation, the object of the invention being to produce such a holder or support as will hold the hose suspended in any fixed position for watering in any desired location, which said holder or support can be adjusted easily and quickly to direct the nozzle on the hose in different or various directions at the will of the operator.

A further object of the invention is to provide the holder in such a manner that it can, when not in use, be folded easily for storage or transportation purposes.

A still further object of the invention is to produce a simple and inexpensive device and yet one which will be exceedingly effective for the purposes for which it is designed.

These objects, I accomplish by means of such structure and relative arrangement of the parts as will fully appear by a perusal of the following specification and claims.

On the drawings, similar characters of reference indicate corresponding parts in the several views.

Figure 1 is a perspective view of the device showing it as it would appear in operation. Fig. 2 is a side elevation of the same showing it in folded position.

Referring now more particularly to the characters of reference on the drawings, I first provide the supporting structure comprising two base members 1 and 2, the same being pivotally connected with each other, as at 3, whereby they may be folded into the same plane.

At one end of the member 1, I provide an annular guide 4 having its upper end open and curved outwardly, as at 5, to allow of the ready insertion of the hose. Hinged to the opposite end of the member 1 is a vertical support 6 rigidly connected to the upper end of which is a spring clip 7. In practice,

the members 1 and 2 may be slightly curved, as shown, so that when the member 2 is extended at right angles to the member 1, the supporting frame will be slightly above the ground level in order that it may be rigidly held in position by the projecting ends of the members 1 and 2. The hose 8 is engaged through the guide 4, the upper or open ends 5 of the guide 4 being sufficiently close together to prevent the hose from jumping out of the guide unless taken therefrom by the operator, such ends 5 being sufficiently resilient for the purpose of admitting or withdrawing the hose from the guide 4. The hose is then engaged into the spring clip 7 against the back of the projecting nozzle 9, which spring clip 7 is of sufficient resiliency as to frictionally engage the hose and hold it from coming out of position until so desired by the operator.

By shifting the member 6 on its hinged point 6^a (which by the way is a sufficiently frictional hinge to prevent too great a looseness) the direction of the nozzle 9 may be changed at will for the purpose of fixing the direction of the spray which discharges from such nozzle. While the hose is held rigidly in the clip 7, it will move freely through the guide 4 so that the altering of the position of the nozzle may be made readily without altering the position of the holder or misplacing any of the structure, including the hose.

When not in use, the device may be readily folded as shown in the drawing for storage or for transportation from one point to another.

From the foregoing description, it will readily be seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention, as defined by the appended claims.

Having thus described my invention, what I claim as new and useful and desire to secure by Letters Patent is:—

1. A holder comprising a base frame comprising two members pivotally mounted and adapted to be set at right angles to each other, a vertical support on one end of one of said base frames, a frictional engaging

member carried by said vertical support and a guide member at the other end of said base frame alined with said frictional engaging member, as described.

- 5 2. A holder comprising a base frame consisting of two members pivotally mounted and adapted to be set at right angles to each other, a vertical supporting member hinged to one of said base members, a frictional engaging member fixed to the top of said supporting member, a guide member at the other

end of said base member alined with said frictional engaging member, the upper end of said guide member being open to admit of the insertion of a hose, as described.

15

In testimony whereof I affix my signature in presence of two witnesses.

JOHN E. HOWELL.
